The ornamental design for a combination level and protractor, as shown and described.

DESCRIPTION

FIG. 1 is a perspective view of the combination level and protractor embodying the design of the present invention;

FIG. 2 is a front elevational view thereof;

FIG. 3 is an end elevational view thereof, the end opposite being a mirror image of the end shown in FIG. 3;

FIG. 4 is a rear elevational view thereof; and,

FIG. 5 is a top plan view thereof, the bottom being decorated identically to the top.

FIG. 1

FIG. 2

FIG. 3

FIG. 5

FIG. 4
